To all whom it may concern:

Be it known that I, Jean Margouleff, a citizen of the United States and a resident of the county of Nassau, city and State of New York, have invented a new, original, and ornamental Design for Shoes, of which the following is a specification, reference being had to the accompanying drawing, forming part thereof, in which:

My design for a shoe is characterized by the formation of the stitching along the instep and around the heel, as best shown in detail in Figs. 2 and 3.

The ornamental design for a shoe, as shown and described.
